UNITED STATES PATENT OFFICE.

EVEN E. THOMPSON, OF MINNEAPOLIS, MINNESOTA.

PUMP STRUCTURE.

Application filed March 15, 1926. Serial No. 94,790.

This invention relates to a distributing device adapted to be used with a pump. As is well known, pumps for pumping water from wells are usually located on a platform and have a pump casing and pump rod extending down to a cylinder in the well, in which cylinder the piston is disposed. It is often desirable to pump the water to different points.

It is an object of this invention to provide a very simple and efficient device which can be readily connected to the pump casing and to various distributing pipes or conduits, said device also having controlling means whereby the water can be distributed as desired.

It is a further object of this invention to provide a distributing device comprising a casing formed as a single casting which can be readily inserted in the pump casing and suitably connected so as to be easily and quickly controlled from the pump platform.

These and other objects and advantages of the invention will be fully set forth in the following description made in connection with the accompanying drawings, in which like reference characters refer to the same parts through the different views and in which:

Fig. 1 is a view partly in front elevation and partly in vertical section of the lower end of a pump mounted on a platform, with the pump casing and cylinder, having the device applied thereto.

Fig. 2 is a horizontal section taken on line 2—2 of Fig. 1 as indicated by the arrows and shown on an enlarged scale.

Referring to the drawings, a portion of a pump platform of ordinary construction is shown at 3. The lower end of the pump body 4 is shown as connected to the platform 3, from which pump extends downwardly the usual pump casing 5. The pump 4 may be of any ordinary and usual construction, operated either by a pump handle or by a windmill or other motor. The pump casing 5 is shown in two sections, the lower one 5^a of which connects with the pump cylinder 6 from which a pipe 7 extends into the supply of water. The usual valve equipped piston or plunger 8 is provided in cylinder 6, connected to the pump rod 9 which extends through casings 5 and 5^a and through the pump 4.

In accordance with the present invention, sections 5 and 5^a of the pump casing are

separated and a casing 10 is provided. The casing 10 is preferably made as an integral casting and has a chamber 10^a therein, preferably cylindrical and having a cylindrical bore at its upper end. Said end is externally threaded and provided with a closing cap 11 having a central bored hub 11^a. The casing 10 has a plurality of circumferentially spaced ports 10^b leading therefrom, through the hubs 10^c, which hubs are threaded to receive the radially arranged pipes or conduits 12 which thus extend from the ports 10^b. A cylindrical valve 13 is provided, closed at its top and fitting in the bore at the upper end of chamber 10^a, said valve having an upwardly extending central stem fitting in the hub 11^a, which stem is rigidly connected to a rod 14 adapted to extend upwardly above platform 3 and have secured thereto a suitable operating handle 15. Valve 13 has a port 13^a therein, adapted to align with any one of the ports 10^b. If desired or necessary, the packing material may be disposed between valve 13 and the cap 11. The casing 10 has a branch or portion 10^d at one side thereof, having a chamber 10^e therein communicating by means of one of the ports 10^d with the chamber 10^a. Portion 10^d is shown as having a hub at its upper end internally threaded to receive the lower end of the pump casing section 5. The lower end of portion 10^d is also shown as having a projecting hub bored to have the rod 9 pass therethrough and externally threaded to receive the stuffing box 16 whereby suitable packing may be placed around rod 9 and between said latter hub and box or cap 16. Casing 10 also has a lower branch or portion 10^f having therein the chamber 10^g communicating through passage 10^h with chamber 10^a, and said portion 10^f has a hub at its lower end internally threaded to receive the upper end of the pump casing section 5^a. Portion 10^f also has an upwardly projecting hub or stem at its upper end bored to have passed therethrough the rod 9 and externally threaded to receive the stuffing box or cap 17 so that packing material may be disposed under the cap 17 and around rod 9.

In operation, if it is desired to deliver the water at the pump 4 in the usual manner, the handle 15 in rod 14 will be turned so that port 13^a aligns with the port 10^b communicating with the chamber 10^a. When the pump is then operated, the water will be

squarely against the inner or bottom wall of the said socket. The operator then uses a hammer, striking the outer plug in the direction of the length of the axle whereby the wheel is jarred loose from the axle and the key thereof and may be quickly removed.

Having described the invention what is claimed is—

A device adapted to be used for removing a wheel from an axle upon which it is keyed comprising a body provided at its opposite ends with alined sockets of different sizes, and anvil plugs fitting in the sockets.

In testimony whereof I affix my signature.

CASH A. CLEMONS.
